DESIGN FOR SUNGLASSES

Joseph Di Cicco, San Marcos, Tex.

Application October 9, 1944, Serial No. 115,697

Term of patent 7 years

(Cl. D57—1)

To all whom it may concern:

Be it known that I, Joseph Di Cicco, a citizen of the United States of America, residing at San Marcos, county of Caldwell, and State of Texas, have invented a new, original, and ornamental Design for Sunglasses, of which the following is a specification, reference being had to the accompanying drawing, forming a part thereof, wherein:

Fig. 1 is a front perspective view of sunglasses showing my new design, and

Fig. 2 is a fragmentary side elevational view of the same.

I claim:

The ornamental design for sunglasses, as shown.

JOSEPH DI CICCO.
